UNITED STATES PATENT OFFICE.

JOHN HORROCKS AND JAMES HORROCKS, OF MANCHESTER, COUNTY OF LANCASTER, ENGLAND.

MACHINE FOR DOUBLING AND WINDING YARN OR THREAD UPON BOBBINS.

SPECIFICATION forming part of Letters Patent No. 297,690, dated April 29, 1884.

Application filed October 19, 1882. (No model.) Patented in England October 22, 1879, No. 4,278; in France April 20, 1880, No. 136,230, and in Belgium April 22, 1880, No. 51,234.

To all whom it may concern:

Be it known that we, JOHN HORROCKS and JAMES HORROCKS, citizens of Great Britain, residing at Manchester, in the county of Lancaster and Kingdom of Great Britain, have invented certain new and useful Improvements 5 in Machines for Doubling and Winding Yarn or Thread upon Bobbins; and we do hereby declare the following to be a full, clear, and 10 exact description of the invention, such as will enable others skilled in the art to which it app pertains to make and use the same, reference being had to the accompanying drawings, and to letters or figures of reference marked there- 15 on, which form a part of this specification.

Our invention relates to doubling and winding machinery wherein the bobbin is mounted on a horizontal axis, and is rotated by the frictional contact of the bobbin with the periphery of the driving-drum; and it has for its object 20 to automatically stop the rotation of the bobbin by causing it to be lifted off the driving-drum when one or more threads break or are absent, so as to enable the attendant to 25 find the broken or absent thread end or ends and tie the same.

The invention consists, essentially, in the combination, with the bobbin and the detector-plate, of appliances to automatically lift the 30 bobbin out of contact with the driving-drum, and for removing the detector-wires out of the path of the angular shaft when one or more of said wires fall into the path of said shaft on the breakage or absence of a thread or threads; 35 and it further consists in the construction of the detector-plate substantially as hereinafter described, and specifically pointed out in the claims.

In the accompanying drawings, Figure 1 is 40 a sectional elevation illustrating two constructions for carrying out our invention. Fig. 2 is an elevation, partly in section and on an enlarged scale, of the mechanism employed for carrying out our invention, and shown on the right side of Fig. 1. Fig. 3 is a plan view of the same. Figs. 4, 5, 6, and 7 are detail views 45 of the detector-plates. Fig. 8 shows a construction of supporting-bracket for the bobbins of a double machine when the mechanism

for lifting said bobbins out of contact with the 50 driving-drum is the same for each bobbin. Fig. 9 is a plan view; and Figs. 10 and 11 elevations of the mechanism shown on the left of Fig. 1, the latter view showing the bobbin out of contact with the driving-drum. 55

In the above-described figures of drawings like letters of reference indicate like parts.

A is the frame, of suitable material and construction to support the operative mechanism. Various constructions of mechanism may be 60 adopted in carrying out our invention, and to better illustrate the same we have shown two such constructions—one on the right and one on the left side of the frame—either one of which may be employed in a single machine, 65 or both may be employed in a double machine, or the one or the other mechanism may be duplicated on opposite sides of the driving-drum in a double machine.

In order that our invention may be better 70 understood, we will first describe the mechanism shown on the right side of the machine for automatically lifting the bobbin out of contact with the driving-drum whenever one or more threads break or are absent, which mechanism 75 we prefer to use in practice.

Referring to the mechanism shown on the right of Fig. 1 and in Figs. 2 and 3, as well as to Figs. 4, 5, 6, and 7, the spindle *h* of the bobbin *H* is mounted in bearing-grooves *b*³, 80 formed in the outer end of the side bars, *I*, of a frame, *I*, that is mounted upon a shaft, *i*, to one of which side bars is pivoted a prop, *I*², that serves to hold the frame up when the bobbin is lifted off the driving-drum *C*. The shaft 85 *i* has its bearings in standards or brackets *i*', secured to a beam, *A'*, of the main frame *A*. A lever, *D*, the forward end of which is or may be slightly bent upward like the outer end of a similar lever, hereinafter described, 90 is pivoted in standards *d*, secured to beam *A*', and said bent end of the lever lies underneath the bobbin *H*. The rear end of the lever has a handle, *D*', and carries the bent wire *D*², hereinafter described, that is adapted to rest 95 upon the horizontal wire *e* of the detector-plate.

G is the angular or ratchet bar, by means of

which the detector-plate is tilted when a thread or threads break or are absent, to release the lever D and lift the bobbin out of contact with the driving-drum.

5 The frame I is automatically returned to its normal position when the lever D is raised to place the bent wire D² upon wire e of the detector-plate by means of an arm, d⁴, projecting laterally from the lever D, which arm 10 d⁴, as the lever D is raised, comes in contact with the prop I², that serves to hold up the frame I, and pushes the lower end of said prop to one side, allowing the frame I to fall and bring the bobbin in contact with the driving- 15 drum. In this construction, after the bobbin has been lifted out of contact with the drum and its momentum arrested by the lever D, the attendant tilts the frame until the prop I² rests upon the beam A', thus enabling him to 20 more readily rotate the bobbin to find and tie the broken or absent threads.

The pivoted detector-plates are constructed with three ribs, e', that limit the movement of the detector-wires E'. In said ribs are formed 25 as many notches or grooves e² as there are detector-wires employed, and said detector-wires are bent, as shown at e', to prevent their being lifted out of the grooves and also to prevent their rotation in said grooves and limit their downward movement when a thread breaks or is 30 absent. The wires are held in the grooves by means of a plate, E², which may be securely fastened to the detector-plate either by forming lugs on its opposite ends, under which the 35 plate may be slid, as shown in Fig. 6, or said plate E² may be attached to the detector-plate by means of a screw, e', and a thumb-nut, E', as shown in Fig. 5.

The threads to be doubled or wound are 40 drawn from cops or from bobbins or swifts arranged in any ordinary manner. Said threads pass each through a slit in a cleaning or guide plate, K, and over a flannel-covered tube, L, to give friction and clean the threads. From 45 the tube the threads pass through the guide hooks or curls e' of the detector-wires E', thence over the pulleys M, mounted in bearings formed in arms m, secured to the upper cross-head, A³, of the main frame A. From the pulleys 50 M the threads descend through guide-loops n, adjustably secured to a bar, N, that has the usual traversing motion for distributing the threads, from which guide-loops said threads pass onto the bobbins, all as plainly shown in 55 Fig. 1. Should, however, one or more of the threads break or be absent, the detector-wires thereof will fall, and their ends project below the detector-plate into the path of the angular shaft G. The latter in its rotation will 60 strike the projecting ends of the wires and tilt the detector-plate forward, thereby moving the wire e from under the bent wire D² and tripping the lever D. The outer end of 65 the lever in its upward movement will carry the bobbin b with it and hold the same out of contact with the driving-drum, the lever at the same time arresting its momentum. The

wire D², in passing behind the wire e, draws the detector-plate E toward it sufficiently to move the projecting ends of the detector-wires 70 out of the path of the angular shaft G. By tilting the frame a little farther upward, the prop I² swings to a vertical position, its lower end resting upon the beam A', thus holding the frame and bobbin clear of the lever and driving-drum, and thus enabling the attendant to rotate the bobbin and find and tie the broken or absent thread or threads. When this has been done and the lever D is lifted again into its normal position, the arm d⁴ 80 pushes the prop I² from under the frame I, which moves downward and again brings the bobbin in contact with the driving-drum.

The mechanism is operated from any suitable prime motor through the medium of the 85 driving-drum shaft, which carries a pulley or pulleys (according as the machine is a single or double one) belted by cross-belts to a pulley on shaft G. (Shown in dotted lines, Figs. 10 and 11.) We have deemed it unnecessary 90 to show this mechanism in detail, as any mechanic at all familiar with this class of machines will readily be able to properly apply and operate the same.

Having now described the mechanism preferably employed by us, we will now describe a modification thereof, which differs but slightly in construction and operation, said mechanism being shown on the left of the machine. 95

B' are inclined guides formed on or attached 100 to brackets B, secured to a carrier-beam, B². When a double machine is made with both sides alike, the inclined brackets B', to guide the ends of the spindles or axes of the bobbins, are or may be made double, as shown in 105 Fig. 8, and secured to a beam, B³, passing from end to end of the frame immediately under the drum-shaft e. One bracket, B, guides and holds the ends of the bobbin on each side of it. Upon the bracket B is adjustably secured, 110 by means of a slot, b, and a set-screw, b', a standard, d, that serves as an adjustable fulcrum for a lever, D, the forward end of which lever is slightly bent upward, and said bent end extends underneath the bobbin when in working position, and nearly the entire length thereof, as shown in dotted lines in Fig. 2. At its rear end said lever is provided with a handle, D', and a loop or eye, d', for the suspension thereto of a weight, d², if desired; or the 115 lever may be weighted. A bent wire, D², is adjustably secured to the rear end of the lever D by means of set-screw d². The end of this bent wire rests upon a wire, e, secured in projections formed on or attached to the detector- 120 plate E, said plates having pivots or trunnions at each end resting in bearing-grooves formed in brackets f, secured to or cast with a beam, F, passing from end to end of the main frame A. The pivoted plate E, by its 125 own weight and the weight of the lever D, is forced against a stop formed by shoulder f' on the brackets f, which hold said plate against movement in that direction. When, however,

one or more detector-wires E' fall from the breakage or absence of a thread or threads, the end of the wire or wires so falling will come in contact with ratchet or toothed wheels 5 mounted on a shaft arranged to rotate immediately below said wires, or with a shaft or bar, G, of triangular or other angular form in cross-section, said shaft rotating in the direction of the arrows, Figs. 1, 10, and 11, and causes the 10 detector-plate E to swing forward, by which movement the wire e will move from under the bent wire D², and allow the lever D to descend by its own weight or by the additional weight d³ and its forward bent end to lift the 15 bobbin H out of contact with the driving-drum C. If desired, the additional weight d³ may be suspended from the detector-plate, said plate being provided with a suitable lug projecting therefrom, as shown in Fig. 6. The 20 bent wire D², in its descent, slides behind its supporting-wire e and tilts the detector-plate E forward and away from the shaft or bar G. This movement of the plate E may be increased or diminished within certain limits by 25 a corresponding adjustment toward or away from the plate E of the standard d, or by varying the angle of the bent wire, or by the adjustment of said wire through the medium of the set-screw d⁴. By this forward motion of the 30 detector-plate E the ends of the fallen detector-wires E', projecting below the detector-plate, are carried out of the path of the rotating bar G. When the bobbin H is held out of contact with the driving-drum by the lever D, 35 which serves also as a brake to arrest the momentum of the bobbin, the attendant can raise said bobbin into bearings b², formed in the upper end of the guides B', by sliding the bobbin-shaft or spindle h up in the grooves b³ 40 of said guides B', and he may then rotate the bobbin to find and tie the thread end or ends. When this has been done, the lever D is lifted by means of the handle D', which releases the detector-plate and allows it to fall 45 back into its normal position, when the bent wire D² may be placed upon wire e to hold the lower end of the lever out of contact with the bobbin, the attendant holding said lever until the tension upon the thread has drawn 50 up the detector-wires out of the path of the angular shaft or bar G.

It will be understood that, instead of the detector-plate hereinbefore described, any other suitably-constructed detector-plate may be employed.

We claim—

1. The combination, with a pivoted detector-plate, the detector-wires thereof, a driving-drum, C, and a rotating shaft, G, of mechanism, substantially such as described, to lift the bobbin clear of the drum when one or more detector-wires fall in the path of shaft G on the breakage or absence of a thread or threads, and automatically carry said wires 65 out of the path of said shaft, as described, for the purpose specified.

2. The combination, with a pivoted de-

tector-plate, its detector-wires, a driving-drum, C, and a rotating shaft, G, of a lever operating to lift and support the bobbin out 70 of contact with the driving-drum, when one or more detector-wires fall in the path of the shaft G on the breakage or absence of a thread or threads, and means whereby said wires are automatically moved out of the path of said 75 shaft, as described, for the purpose specified.

3. The combination, with the driving-drum C, the detector-plate E, and detector-wires E', of the rotating shaft G, prism-shaped in cross-section, and mechanism, substantially 80 such as described, for positively lifting the bobbin clear of the driving-drum when one or more of the detector-wires fall in the path of the shaft G on the breakage or absence of a thread or threads, and devices for automatically 85 moving said wire or wires out of the path of said shaft, as described, for the purpose specified.

4. The combination, with the driving-drum, the detector-wires and detector-plate, and a 90 rotating shaft to tilt said plate when one or more of said wires fall by reason of the breakage or absence of a thread or threads, of a lever operated by the movement of said detector-plate to lift the bobbin out of contact 95 with the driving-drum, appliances, substantially such as shown and described, to hold said bobbin in the latter position independently of the lever, and a tripping device operated from said lever to return the bobbin into 100 contact with the driving-drum, as set forth.

5. The combination, with the driving-drum, the bobbin-support, the detector-wires E', detector-plate E, wire e, and shaft or bar G, of the adjustable lever D and the adjustable 105 bent wire D², all arranged for co-operation substantially as and for the purpose specified.

6. The combination, with the driving-drum, the bobbin-frame I, and the prop I², of the lever D, and the tripping-arm d⁴, substantially 110 as and for the purpose specified.

7. A detector-wire bent as at e², in combination with the detector-plate E, constructed with longitudinal ribs e', channeled as at e², the retaining-plate E², and means, substantially such as described, for rigidly securing plate E² to plate E, substantially as shown, and for the purpose specified.

8. The combination, with a driving-drum, a pivoted bobbin-frame, a lever, a stop to hold said lever out of contact with the bobbin-frame or its bobbin, and tripping devices to trip the stop on the breakage or absence of a thread, of a weight connected with the lever, substantially as and for the purpose specified.

In testimony whereof we affix our signatures in presence of two witnesses.
